GRINDING DISK

Ingle R. Shue, Beloit, Wis., assignor to Gardner Machine Company, South Beloit, Ill., a corporation of Illinois

Application March 17, 1939, Serial No. 262,365

4 Claims. (Cl. 51—209)

The invention relates generally to grinding means, and more particularly to a grinding disk, one face of which is utilized for grinding.

The general object of the invention is to provide a new and improved grinding disk so constructed as to provide for expansion due to heat such as would cause the grinding face to become distorted out of the plane to which it was originally trued, the structure of the disk being such that a large factor of safety is provided so that it may be operated at high speeds and under heavy loads.

More specifically, it is an object to provide a grinding disk having slots to provide for expansion of the disk due to heat and thus avoid distortion of the grinding face out of the plane to which it is trued, and also having reenforcing structure of such nature that the disk is not materially weakened by the slots.

It is also an object to provide a novel method of making a disk of the foregoing character.

Other objects and advantages will become apparent from the following description taken in connection with the accompanying drawings, in which:

Figure 1 is a perspective view, partially broken away, of a grinding disk embodying the features of the invention.

Fig. 2 is a view similar to Fig. 1 showing a modified form of grinding disk.

Fig. 3 is a view similar to Fig. 1 but showing another modified form of the grinding disk.

Fig. 4 is a view similar to Fig. 1 of another modified form of grinding disk comprising a plurality of separate segments.

Fig. 5 is a perspective view of a mold for making disks of the character shown in Fig. 1.

Fig. 6 is a transverse section of the mold shown in Fig. 5.

In present grinding practice, grinding disks are often rotated at such high speeds and so much stock removal is effected thereby that a large amount of heat is generated and the disk tends to expand. Such disks are annular in form and are mounted on a metal supporting wheel, the grinding being done by the face of the wheel. It has been noted that when the heat reaches such an extent that the whole mass of the disk and the supporting wheel have a considerable temperature rise, the disk tends to raise in its central portion and assume a somewhat conical form. Such distortion of the disk is due to the fact that the disk proper has a different coefficient of expansion from that of the supporting wheel and, since the disk is bolted to the sup-

porting wheel at a plurality of points distributed over the entire area thereof, the difference in expansion between the supporting wheel and the disk proper causes the latter to assume a conical form.

The accuracy of grinding operations performed by the disk is obviously affected by such distortion of the disk. A disk is usually trued before it has become thoroughly heated. Thus when the expansion occurs, the distortion causes the grinding face of the disk to vary from the original plane to which such face was trued.

It is therefore desirable to construct the disk in a manner to eliminate such conical distortion. It has been found that, by placing narrow radially extending slots in the disk, it can expand the necessary amount without producing a distortion of the face of the disk. However, such slots would tend to weaken the disk unless the disk also embodied such structure as would rigidly tie all parts of the disk together. The need for physical strength in the disk is particularly great because of the generation of heat. In other words, if the work done on a disk is sufficient to produce such heat as would cause undue expansion, then such work also places severe stresses on the disk, thereby requiring a structure not only compensating for any weakening produced by the means for eliminating undesirable expansion, but also a structure capable of carrying the high stresses.

Any slots or holes in the grinding face of the disk also affect the cutting action of the disk. It is therefore necessary to arrange the radial slots herein disclosed in such a manner that the amount of open space in the grinding face of the disk will remain substantially constant as the disk wears down, so that the cutting action of the disk will correspondingly remain constant. Since the expansion due to heat, when it occurs in the direction of such slots, is relatively small in actual dimension, the slots may be correspondingly narrow. Moreover, it is desirable to keep the slots as narrow as is practicable in order to prevent the work from being caught in the slots as it passes thereover.

In the preferred embodiment of the invention illustrated in Fig. 1 of the drawings, the supporting wheel is indicated at 10 and is of the type which is adapted to be rigidly secured to the spindle of a grinding machine. The grinding disk, indicated generally at 11, is provided with a plurality of radially extending slots 12 which provide space for the expansion of the disk and thereby avoid distortion of the grinding face. For

reasons which will be more fully explained in the description of the process of making these disks, the slots 12 do not extend clear through to the front face of the disk when made, but a thin layer 13 is left thereover, which layer very quickly wears off or is removed in truing the disk so that the slots, after the disk has been in use for a short time, open to the grinding face thereof.

Since the slots 12 tend to weaken the disk because of the fact that they divide it into sections, the disk is so made as to include structure to compensate for such weakening effect as well as to provide a maximum of strength since disks of this character are subjected to heavy stresses during operation. Every grinding disk is provided with means for attaching it to the supporting wheel. In this instance nuts 14 are embedded in the rear portion of the disk by which the disk may be attached to the supporting wheel by bolts extending therethrough. Anchoring devices of this character are preferably distributed throughout the entire area of the disk. Since that portion of the thickness of the disk in which the anchoring devices are embedded is relatively small, there is no necessity for having the radial slots 12 extend into that portion of the thickness of the disk. Consequently the slots 12 have a depth substantially equal to the thickness of the usable portion of the disk.

Since the slots divide the usable portion of the disk into sections which are not integrally connected to the adjoining sections themselves, the portion of the disk in which the anchoring devices are embedded is made of sufficient strength to rigidly tie these sections together. Thus the disk may be said to be divided into a front layer 16 in which the radial slots are located, and a rear layer of unitary construction which serves to tie all parts of the disk together as a unit. To give the rear layer sufficient strength to perform this function, it is preferably reenforced as by means of a wire mesh 15 embedded therein. The mesh preferably is coextensive with the area of the whole disk and is located between the nuts 14 and the rear face of the disk. Thus stresses on any section of the disk will be transmitted throughout the disk by the rear layer and will be distributed uniformly over all the anchoring devices. By such construction each section between adjacent radial slots is not dependent solely on the anchoring devices within that section. The structure thus provides a large factor of safety and is particularly desirable for the very character of the work necessitating provision for expansion.

In Fig. 2 there is disclosed a disk having a greater thickness than the disk shown in Fig. 1. With a greater thickness the slots, indicated in this instance at 20, are so arranged that the usable portion of the disk itself has greater strength. Thus each slot may have a depth substantially half the thickness of the usable portion of the disk, and the slots may be arranged in two rows, one above the other, with the slots in one row in staggered relation to the slots in the other row. The rear layer of the disk is constructed similarly to the disk shown in Fig. 1. Thus while the rear layer rigidly ties the various sections of the disk together at the rear face thereof, the staggered relation of the slots in the two rows provides a tying of the respective sections to each other adjacent the front face of the disk so that the weakening effect of the slots is much less than if each slot extended the

full thickness of the usable portion of the disk.

Since the slots materially affect the cutting action of the disk, it is desirable to have the lower or rear edge of the slots in the front or upper row located in substantially the same plane, indicated by the dash and dot line 21, as the front edge of the slots in the lower or inner row.

While the slots in the two rows may have their adjacent edges located in exactly the same plane, they may, if desired, overlap slightly and extend beyond such plane, as shown in Fig. 3. Thus, while there may be a slight change in cutting effect for a small part of the thickness of the disk, there is ample provision made for expansion at all times throughout the wearing of the disk.

In cases of disks of large diameter it is common practice to make the disk in a plurality of separate segments, each segment being of convenient size to mold and to handle. The segments are mounted on a unitary supporting wheel with a small space between each segment so that each segment may be accurately positioned. Such space obviously provides room for expansion but as a rule the spaces are insufficient in number to entirely eliminate undesired expansion. For that reason additional space is provided for expansion by means of radial slots.

In Fig. 4 I have illustrated a segmental type of disk embodying the features of the invention. Thus the disk comprises a plurality of segments, each indicated generally at 25, the disk in this case comprising four such segments. The space between the respective segments is indicated at 26. Each segment is constructed in a manner similar to the disk shown in Fig. 1. Thus a rear layer 27 is provided which extends over the whole area of the segment and constitutes the unusable portion of the disk. In the rear layer 27 is embedded the reenforcing means comprising wire mesh 28 and the anchoring devices comprising the nuts 29.

The front layer, constituting the usable portion of the disk, is provided with radial slots sufficient in number and size to compensate and provide room for expansion due to heat. In the present instance there is provided a plurality of radial slots 30 which extend from the center hole in the disk through to the periphery thereof. Because of the large size of each segment it may also be desirable to provide further slots 31 which extend from the point midway between the center and periphery of the disk out to the outer periphery. Thus the radial slots 30 and 31, together with the space between the various segments, provide ample room for expansion of the disk due to heat. Moreover, in each segment the sections of the disk between the respective slots are rigidly tied together by means of the rear layer 27 and its reenforced construction, so that the stresses on any section within a segment is uniformly distributed over all the anchoring devices within that segment.

The shorter form of slots, such as those shown at 31, may also be used in disks of the forms shown in Figs. 1, 2 and 3.

The heat expansion slots shown in the various forms of the invention need not be of any great width since the expansion due to heat is of relatively small dimension. Moreover, it is preferable not to make the slots of any great width in order that the work in passing over the surface of the disk may not be caught in such slots. In practice these slots are preferably $\frac{1}{8}$ to $\frac{1}{2}$ of an inch in width.

In Figs. 5 and 6 I have disclosed a mold utilized in the method of making disks of the character herein disclosed. The particular mold shown in Figs. 5 and 6 is arranged for making disks of the character shown in Fig. 1. The mold comprises a base plate 40 adapted to be placed on the platen of a press. Surrounding the base is a ring 41 and mounted centrally of the base is a core 42.

In the process of making the disk a wire mesh 43 cut to fit the mold is first placed on the base plate, and the anchoring devices are placed thereover. Molding material is then spread over the wire mesh and tamped so that the mesh and anchoring devices are thoroughly embedded therein. This constitutes the rear layer of the disk. To form the radially extending slots in the disk, bars or strips 44 are placed over the rear layer. Preferably such bars are supported at their inner ends by the cores 42 and extend outwardly through the ring 41 for support thereby. Abrasive material mixed with a bond is then filled into the mold, completely covering the bars 44 and extending to a height considerably thereover; for example, to the level shown by 25 the line 45 in Fig. 6. The abrasive material is then pressed, the compacting being carried only down to a level above the upper edge of the bars 44, for instance, to the level indicated by the line 46. This leaves a slight covering over the 30 bars and consequently over the slots, but it is desirable in that the platen of the press does not contact the bars 44. Thus the entire pressure is applied to the abrasive material and none is supported by the bars.

To remove the disk from the mold, the bars 44 are first withdrawn outwardly and then the disk itself may be removed from the mold in the usual manner and undergo any further treatment desired. The bars 44 thus provide the radially extending slots in the disk.

It is obvious that in the process of making the disks shown in Figs. 2 and 3, or the disk shown in Fig. 4, other bars located at different heights or of different lengths may be set into the mold to produce the correspondingly located slots.

From the foregoing description it will be apparent that I have provided a grinding disk which is so constructed as to provide space for expansion of the disk due to heat so that the grinding face of the disk will not become distorted out of its plane. The disk, however, is of great strength because of the fact that the various sections of the disk between the slots are rigidly held together by a reenforcing layer at the rear of the disk coextensive with the area of the disk. The stresses exerted on each section of the disk are thereby distributed throughout the disk and the anchoring devices uniformly sustain the stress exerted at any point. The slots may be arranged in a single row, as shown

in Fig. 1, or in a plurality of rows, as shown in Figs. 2 and 3. If the latter, the slots in each row are staggered relative to the slots in the other row so that a further rigidity and connection between the various sections is thereby provided. The slots may extend from the inner to the outer periphery, as shown in Figs. 1, 2 and 3, or additional slots may also be provided which are located only in the outer portion of the disk, as shown in Fig. 4.

I claim as my invention:

1. A grinding disk adapted to be detachably secured to a supporting wheel comprising, in combination, a front layer having a plurality of radially extending slots arranged in two series, one series being in the front part of the front layer and the other series being in the rear part of the front layer with the slots in one series in staggered relation to the slots in the other series, and a rear layer having reenforcing means rigidly supporting the disk as a whole and tying all parts thereof together as a unit.

2. A grinding disk of the character described comprising, in combination, a body of abrasive material having a plurality of radially extending slots in the usable portion thereof, the slots being arranged in two or more series, the adjacent edges of the respective series of slots being located in substantially the same plane whereby only one series of slots will be open to the front face at any time throughout the wear of the disk to produce a uniform cutting action, and reenforcing means in the rear part of the disk rigidly tying all sections of the disk together.

3. A grinding disk of the character described comprising, in combination, a front layer having two series of slots with the slots in one series arranged in staggered relation to the slots in the other series, the rear plane of the front series being substantially coincident with the front plane of the other series whereby only one series of slots is open to the grinding face of the disk at any time throughout the wear thereof, and a rear layer provided with reenforcing means for uniformly distributing the stresses on the disk throughout the area thereof.

4. A grinding disk of the character described comprising, in combination, a plurality of segments adapted to be secured to a supporting wheel to form a complete disk of annular form, each segment having one or more radial slots extending from the inner periphery to the outer periphery and one or more radial slots in alternate relation to the first-mentioned slots extending from the outer periphery but terminating short of the inner periphery, the slots having a depth substantially equal to the usable portion of the disk, and reenforcing means and anchoring devices located in the rear portion of each segment.

INGLE R. SHUE.
